DEFOAMING COMPOSITION AND PROCESS

Rudolph H. Larsen, San Francisco, Calif., assignor to Fred Bressee, Jr., doing business as "Balab," Hillsborough, Calif.

Application January 19, 1942, Serial No. 427,305

5 Claims. (Cl. 127—50)

1

This invention relates generally to compositions and processes for eliminating foam and for suppressing its formation in the sugar industry.

In various sugar manufacturing processes, the foaming of liquors undergoing treatment tends to interfere with efficient operation, and in general it is distinctly detrimental. It has been found that foaming can be eliminated to some extent by the use of vegetable oils, such as cocoanut oil, which is added to the liquors in small quantities at various points in the process. Such oils are not as effective as desired, and they do not have a sustained suppressing action. In addition, such oils are relatively expensive, particularly when used in sufficient amounts to control foam formation to a substantial degree.

It is an object of the present invention to provide a composition which will effectively eliminate or kill foam in liquors undergoing treatment in sugar manufacturing processes, and which will also have a sustained action in suppressing formation of foam.

Another object of the invention is to provide a defoaming process which can be used in the presence of lime, without giving an undesirable soap reaction or saponification.

A further object of the invention is to provide a defoaming composition and method which can be used to advantage in sugar-containing liquors being subjected to vacuum evaporation.

Further objects of the invention will appear from the following description in which the preferred embodiment has been set forth in detail in conjunction with the flow sheet.

My defoaming composition consists of a fatty acid together with a hydrocarbon. The fatty acid is preferably of vegetable origin, as for example one obtained from soy bean, cocoanut, or corn oil. Such fatty acids are produced as by-products in the refining of vegetable oils. For example, in the refining of such oils to free them of their fatty acid content, it is customary to react the fatty acid content with sodium hydroxide, and to separate out the precipitate which is termed "fatty oil foots." The soap content of the "foots" is then broken down by reaction with sulfuric acid, after which the resulting fatty acid is washed to free it of any remaining mineral acid content. The commercial by-product obtained in this fashion contains from 50 to 60% free fatty acid, and is free of glycerin. Usable fatty acids can also be obtained as by-products in the hydrogenation process for the refining of vegetable oils, or by fat splitting reactions.

In conjunction with the fatty acid I employ an

unsaturated hydrocarbon, and particularly one obtained from a naphthenic, asphaltum or paraffine base, or combinations of the same. Commercial products of this character are available on the market, and are known by various names including "unsaturated extract oil" and "lube oil extract." Saturated hydrocarbon oils such as "white oil" can be mixed with the fatty acid and used with some effectiveness, but not with the effectiveness of unsaturated hydrocarbons.

In general, various proportions can be used, and I have secured good results by using from 30 to 40% by weight of the commercial fatty acid product, together with from 70 to 60% of the unsaturated hydrocarbon product. The two materials are freely miscible, although they do not appear to enter into chemical reaction.

In using the composition described above, small quantities are continuously added to the liquors undergoing treatment at various points in the sugar manufacturing process. The points at which the composition is introduced will depend upon the particular plant process employed. One operation to which the composition can be applied to advantage, and which is utilized in all modern sugar plants, is the liming and carbonating of the sugar juice preparatory to filtering the material. Relatively small amounts of the composition introduced at this point suffice to eliminate or kill foam and to suppress foam formation during the subsequent filtering operation. Sulfurizing operations such as are employed for decolorizing sugar juice or syrup are also subject to foaming. Here again the composition can be used to advantage to eliminate foam difficulties during such treatment and during subsequent clarification by filtration. Small additions of the composition can also be made immediately before and during concentration by vacuum evaporation. For example, small amounts can be continuously added to the juice entering the first effect of the evaporating equipment, and to syrup entering the subsequent effects, or occasionally added as needed. It has been observed that when my composition is added in this fashion, it not only tends to prevent and suppress foam formation, but in addition it serves to minimize formation of troublesome scale upon the evaporating tubes. In this connection it should be noted that compositions which have been used in the past, such as cocoanut oil, do not tend to lessen scale formation in the evaporator, and in fact seem to augment troublesome accumulation of solids upon the evaporator tubes by formation of calcium

soaps. Such calcium soaps are not formed when my composition is employed. Foaming can be prevented in the vacuum pans where the sirup is further concentrated by using the composition as described.

In different plant processes operations to which the composition is introduced depend somewhat upon the particular procedure employed and upon the type of sugar juice being treated. In order to indicate one practical way of using the composition, the drawing shows a typical flow sheet for a plant process for beet sugar. To briefly outline this flow sheet, the beets after being cleaned are sliced at 10, and then subjected to a suitable treatment for juice extraction 11, which may be by diffusion or other methods. The juice is then intermixed with milk of lime and subjected to carbonation at 12. The milk of lime is prepared in a slaking operation 13, where dry lime is intermixed with "sweet water." The material is then subjected to filtration 20, after which the filtrate is subjected to further carbonation 14, and again to filtration 15. For decolorizing, the juice is then subjected to the sulfurizing operation 16, where it is contacted with sulfur dioxide gas, after which it is again subjected to filtration 17. The purified and decolorized juice is now subjected to vacuum evaporation at 18, by use of multiple effect vacuum evaporators.

Following concentration, the sirup is subjected to further sulfurizing treatment 19, after which it is filtered at 21, and then sent to the first crystallizing vacuum pan 22. After further concentration in this treatment, with partial crystallization of the sugar, the material is subjected to centrifuging 23, which removes the crystallized sugar. The remaining sirup is treated in the second vacuum pan 24, and after further centrifuging at 25, the remaining sirup is sent to the third vacuum pan 26. Final centrifuging 27 of the sirup from the last vacuum pan yields molasses and sugar which is mixed back at 28 with the sirup entering the vacuum pan 24. Sugar from centrifuging 25 is also mixed back at 29 with the sirup entering vacuum pan 22.

Points of introduction of the composition described above have been indicated in the flow sheet and designated by letters A to G inclusive. These points of introduction are as follows:

- A. Lime slaking operation.
- B. The first carbonation operation.
- C. The second carbonation operation.
- D. The vacuum evaporation operation, by additions to the material entering each effect.
- E. The first vacuum pan commonly termed the "white pan."
- F. The second vacuum pan commonly termed the "high raw pan."
- G. The third vacuum pan commonly termed the "low raw pan."

In certain sugar plants the molasses is subjected to further treatment known as the "Steffen" process, in which the molasses is diluted and limed, heated, and precipitated tricalcium sucrate removed in a filter. The sucrate is then returned to the main process. Foaming in this process can also be alleviated by additions of small amounts of my composition.

In the above flow sheet a total consumption of 6.9 gallons of my composition was employed each twenty-four hours, where 800,000 pounds of sugar was being manufactured from 297 tons per hour

5 of the raw beet juice. This total amount was distributed fairly equally between the different points of introduction, including the "Steffen" process, and was introduced by use of suitable feeding devices capable of adding the material by

10 drops at a regulated rate.

The plant process described above and as shown in the flow sheet gave considerable difficulty with foam formation when using such defoaming materials as cocoanut oil. These difficulties were 15 completely overcome by the use of my composition and process. In addition, my process resulted in an economy with respect to the amount of defoaming composition required, and a marked betterment in general operating efficiency was 20 noted.

I claim:

1. A defoaming composition for sugar syrup comprising a fatty acid of vegetable oil origin, the fatty acid being free of glycerine and obtained by removal from foots resulting from the 25 refining of vegetable oil by treatment with alkali and subsequent acidulation with sulphuric acid, together with an unsaturated extract oil of mineral oil origin.

2. A composition for suppressing foaming during treatment of sugar syrup, consisting of from about 30 to 40% of a fatty acid, the fatty acid being free of glycerin and obtained by removal from foots resulting from the refining of vegetable oil by treatment with alkali and subsequent acidulation with sulphuric acid, together with from about 70 to 60% of an unsaturated extract oil of mineral oil origin.

3. In a process for suppressing foaming during treatment of sugar syrup, introducing into the sugar syrup a mixture comprising a fatty acid, the fatty acid being free of glycerin and obtained by removal from foots resulting from the refining of vegetable oil by treatment of alkali and subsequent acidulation with sulphuric acid, together with an unsaturated extract oil of mineral oil origin, the amount of the mixture added being insufficient to cause contamination of the sugar content.

4. In processes for the treatment of sugar syrup involving intermixing of the syrup or juice with lime followed by carbonation of the mixture and filtration of the carbonated material, the improvement consisting of suppressing foam formation by introducing into the syrup a mixture comprising a fatty acid of vegetable oil origin, the fatty acid being free of glycerin and obtained by removal from foots resulting from the refining of vegetable oil by treatment with alkali and subsequent acidulation with sulphuric acid, together with an unsaturated extract oil of mineral oil origin, the amount introduced being insufficient to cause contamination of the sugar.

5. A defoaming composition consisting of a glycerine free fatty acid of vegetable oil origin together with an unsaturated extract oil of mineral oil origin.

RUDOLPH H. LARSEN.
